(57) **CLAIM**

The ornamental design for a rocking chair, as shown and described.

DESCRIPTION

FIG. 1 is a perspective view of a rocking chair showing the new design;

FIG. 2 is a front elevation view thereof;

FIG. 3 is a back elevation view thereof;

FIG. 4 is a left-side view thereof;

FIG. 5 is a right-side view thereof;

FIG. 6 is a top plan view thereof;

FIG. 7 is a bottom plan view thereof;

FIG. 8 is another perspective view of the rocking chair with exemplary draped blankets; and,

FIG. 9 is an enlarged view of the encircled portion in FIG. 1.

The broken lines of FIG. 8 depicting draped blankets represent environmental structure that forms no part of the claimed design. The dash-dot lines in FIG. 1 and FIG. 9 illustrate the boundaries of the enlarged view indicators and form no part of the claimed design. The remainder of the broken lines depict portions of the rocking chair that form no part of the claimed design.
